UNITED STATES PATENT OFFICE.

JOSEF HASLAUER, OF MUNICH, GERMANY.

VOLTMETER.

Application filed October 10, 1925, Serial No. 61,803, and in Germany August 19, 1924.

The invention relates to voltmeters, more particularly pocket voltmeters, for direct and alternating currents. Its object is to provide a simple instrument, which can be 5 cheaply made and is sufficiently accurate to indicate, with good or fair approximation, the voltage of the current in a circuit in cases where it is desired to ascertain to what order of values the voltage belongs, rather than to measure with precision.

According to the invention a hollow cylinder of magnetic material is so disposed around the armature and in relation to the coil producing the magnetic flux, that nearly 15 the whole of the flux passes through this cylinder, but the latter is provided with a slot or gap in which there is a field whose strength varies, from one part to another, and the armature, which is biased in the 20 usual way, tends to move into the strongest part of this field.

The invention is illustrated in the accompanying drawing, which shows an embodiment thereof,

25 Figure 1 being a section perpendicular to the axis of the instrument, and

Fig. 2 a section on the line A—B of Fig. 1;

Fig. 3 shows, developed in a plane, the 30 cylindrical casing already referred to;

Fig. 4 shows another modification of the armature;

Fig. 5 is a front elevation of the instrument;

35 Figure 6 is a view corresponding to Figure 3 except that the opening *c* is shown as having curved sides.

Within the outer casing *k* of insulating material, which has a glass face *l*, there is 40 an annular iron box *a*, the inner circumferential wall of which is an iron cylinder *b* having a slot *c*. The width of the latter decreases from one end to the other, but instead of being tapered with straight lateral 45 edges, as shown in solid lines in Fig. 3, the edges may be curved, as shown in broken lines. Within the box, and seated upon the cylinder *b*, there is a coil holder *d*, with a coil of resistance wire wound thereon, the 50 ends of the coil being connected to posts *e*. Within the cylinder *b* is mounted the armature *f*, which may be a segment of a cylinder, as shown in Fig. 1, or a complete cylinder, as shown in Fig. 4. To the armature 55 spindle are attached a pointer *h* and one end of a non-magnetic spiral spring *g*. The

armature spindle is slightly eccentric in relation to the cylinder *b*. The scale *i* is marked on the box *a*.

When the terminals of the coil are connected to a live circuit, the coil generates a magnetic flux which is almost wholly confined to the iron box *a* and cylinder *b*, but there is in the slot *c* a stray field, whose strength varies from one end to the other. 60 The armature *f*, which by virtue of its eccentric mounting can swing into the slot, tends of course to occupy the strongest part of the field.

The instrument shown can be used for direct and alternating currents, but different scales are required for these two kinds of current.

What I claim as my invention and desire to secure by Letters Patent of the United 75 States is:—

1. In a voltmeter, the combination with an outer casing of insulating material, of a field magnet coil in said casing, an annular box of magnetic material within said casing and completely enclosing said coil, the inner wall of said box being a cylinder having a slot varying in width from one end to the other, and an eccentrically mounted armature movable interiorly of said cylinder. 80

2. In a voltmeter, the combination of an outer casing of insulating material having a transparent glass face therefor, an annular iron hollow member arranged concentrically within said casing, the inner wall thereof being substantially thicker than the side and outside walls and provided with a slot disposed circumferentially of the inner wall and having its longitudinal side walls tapered towards each other, a coil holder arranged about the inside of the inner wall of the member and having a coil of resistance wire wound thereon, posts carried by the casing and receiving the ends of said resistance wire, an armature operating within 90 said inner wall, a spindle for said armature disposed eccentrically of the axis of said inner wall, a pointer for the spindle and operating to indicate over a scale below the glass face, and a balance spring disposed 95 about the spindle and operating to yieldably hold the armature in a predetermined position and the pointer at zero on the scale. 100

In witness whereof I have signed this specification.

JOSEF HASLAUER.
